MACHINE FOR HAND SEAMING IN VACUUM

Gerald L. Ardon, Seattle, Wash., assignor to
Continental Can Company, Inc., New York,
N. Y., a corporation of New York

Application September 7, 1937, Serial No. 162,820

9 Claims. (Cl. 113—23)

The invention relates generally to container sealing machines and has for an object to provide a novel, simple and efficient, hand actuated seaming machine for sealing, in a vacuum, cans containing fruits, vegetables, salmon or like products.

In its more detailed nature the invention resides in the provision of a vacuum seaming chamber, a door through which access may be had to said chamber, means including a manually actuated valve for bringing about and relieving an evacuated condition in said chamber, a can rotating chuck in the chamber, seaming means manually engageable with a can rotated by said chuck, a can holding pad movable toward and from the chuck, and novel stop devices preventing the movement of a can into engagement with the chuck until the negative pressure controlling valve becomes fully effective.

Another object of the invention is to provide novel means for mounting the seaming devices so as to adapt them to engagement with varied sizes of cans.

Another object of the invention is to provide a simple door structure for sealing the vacuum seaming chamber, and control valve equipment for bringing about and relieving an evacuated condition in said chamber and effective to prevent opening of the door until the chamber evacuated condition is relieved.

With the above and other objects in view which will more fully appear, the nature of the invention will be more clearly understood by following the description, the appended claims, and the several views illustrated in the accompanying drawings.

In the drawings—

Figure 1 is a right hand elevation of a machine embodying the invention.

Figure 2 is an enlarged left hand elevation of the major upper portion of the machine.

Figure 3 is a front elevation of the parts shown in Figure 2.

Figure 4 is a horizontal section taken through the axis of the chuck drive shaft.

Figure 5 is a horizontal section taken on the line 5—5 on Figure 1, the valve closed position of the handle being shown in full lines, the nearly open position in dotted lines, and the fully open position in dot and dash lines.

Figure 6 is a detail vertical cross section taken through the axis of the chuck, the can being shown raised to the partially lifted rod stopped position, in dot and dash lines.

Figure 7 is a detail horizontal section taken on the line 7—7 on Figure 3.

Figure 8 is a plan view of the machine, the frame standard and the chuck driving shaft being shown in horizontal cross section, and the valve handle being shown in the valve open, stop rod retracting position.

Figure 9 is a detail vertical section taken on the line 9—9 on Figure 8.

Figure 10 is a detail plan view of the adjustable, eccentric rock shaft bearing member.

In the drawings, in which like numerals of reference indicate like parts in all of the figures, I have disclosed one form of machine embodying the principles of the invention and which includes a frame standard 5, supported on a base 6, and provided at its upper end with a table portion 7 on which an electric motor 8 is removably mounted.

The framing also is formed to provide spaced vertical bearings 9 and spaced horizontal bearings 10. A shaft 11 is rotatably mounted in the bearings 9, and a shaft 12 is rotatably supported in the bearings 10, said shafts being connected in driving relation by bevel gears 13. A U-shaped housing 14 is removably mounted on the framing and completes a gear-box-like formation about the gears 13.

At its rear end the shaft 10 carries a large spur gear 15 to which rotation is imparted by a small driver pinion 16 carried by the drive shaft of the motor 8. A protective guard 17, secured as at 18 upon the frame standard, provides a suitable protective housing for the gears 15 and 16.

A vacuum chamber housing 19 is secured as at 20 upon the frame standard and includes an open front adapted to be closed by a door 21 hinged as at 22 to the housing and carrying a sealing gasket 23 for engaging the face 24 defining the housing opening and effective to provide a substantially airtight seal. The door preferably includes a handle portion 25.

A can supporting column 26 is vertically reciprocable in a guide bearing 27 adjustably supported as at 28 upon the frame standard 5. This column passes through an oil seal bearing 29 provided therefor in the bottom of the housing 19 into the interior of said housing. At its lower end the column 26 is recessed as at 30 to receive the bifurcated end 31 of a crank lever pivoted intermediate its ends as at 32 upon an extension of the housing support 28. The remaining free end of the lever is bifurcated as at 33 and straddles a control rod 34 to which said lever end is pivotally secured as at 35. The rod 34

is thus connected to move with the column 26. A stop pin 36, projecting from the frame standard 5, serves to limit downward movement of the column.

- 5 Upon its upper end, the column 26 carries a can supporting pad 37. The pad is equipped with an axially depending standing 38 rotatable in a sleeve bearing 39 provided therefor in the column 26. This standard extends through a hardened bearing ring 40 supported upon the upper end of the column and upon which the pad has an anti-thrust bearing as indicated at 41.

- 10 15 A treadle 42 is pivotally mounted as at 43 adjacent the lower end of the standard 5 and is connected, intermediate its ends as at 44, with the control rod 34. The spring 45 normally holds the rockable lever in the column lowered, control rod raised position.

- 20 25 At its lower end, the driver shaft 11 carries a can rotating chuck 46 removably secured thereon as at 47 and extending into the upper portion of the vacuum chamber. The chuck equipment includes a spindle 48 rotatable in an oil seal bearing 49, and the chuck proper 46. The can supporting pad 37 preferably is removably secured as at 50 so that it may be removed and replaced by other pads, and the chuck equipment includes a chuck plate 51 similarly removable so that replacements may be used, thus adapting the machine to the seaming of cans of varied diameters. The adjustable bearing 27, 28 adapts the machine to the seaming of cans of varied lengths.

- 30 35 A stop rod 52 is reciprocably mounted in transverse relation to and in the plane occupied by the control rod 34. The rod 52 is slideable in and projects from the ends of a long sleeve bearing 53 secured as at 54 upon the frame standard 5. At 40 45 its ends adjacent the control rod 34 the bearing sleeve 53 is counterbored as at 55 to receive the enlarged stop head 56 forming a part of the rod 52. A spring 57 is coiled about the rod 52 in the counterbore 55 and serves normally to project 50 55 the stop head 56 to a position close to the control rod, a limiting collar 58 engageable with an end of the sleeve bearing 53 serving to limit outward movement of the rod 52 just short of contact with the control rod 34. At its other end the rod 52 55 carries an abutment head 59 which serves a function soon to be described.

- Toward its upper end, the control rod 34 slides in a bearing member 60 and carries a stop collar 61 adjustably secured thereon as at 62 in position 55 for engaging the projected stop head 56 and limiting the amount of lift that can be imparted to a pad supported can when said stop head is in its effective or normal position. The parts are so arranged and proportioned that so long as the 60 stop head 56 is projected the stop collar 61 will engage it and prevent the pad from lifting a can all the way into engagement with the rotating chuck. In practice, the stop devices halt can movement when the loosely resting cover of the can is spaced as at 64, about one sixteenth of an inch from the chuck. See Figure 6.

- An air duct 65 affords communication between the interior of the housing 19, or the vacuum chamber, and one leg 66 of a three-way valve. 70 Another leg 67 of the valve is open to atmosphere, and the third leg 68 is connected by a pipe line 69 with an exhauster or any suitable negative pressure source (not shown). The rotor 70 of the valve is equipped with a T-shaped communication control opening 70' and is de-

signed to be oscillated through 90° during the performance of its control function by a handle member 71.

The valve handle 71 carries a lever extension 72 having a bifurcated end 73 which straddles the stop rod 52 and is engageable with the abutment head 59 carried on said rod during movement of the valve rotor to the fully open or chamber-evacuating position, said engagement taking place just prior to attainment by said valve of its fully open condition. See the dotted lines in Figure 5. It should be understood that in the so-called closed position, see full line position of the handle 71 in Figure 5, communication is had between the housing chamber and atmosphere, 10 15 relieving the evacuated condition in said chamber and permitting opening of the closure door 21. In the open position of the valve, see the dot and dash line position of the handle 71 in Figure 5, communication is had between the vacuum chamber and the exhauster or source of negative pressure, the seaming operation can be performed under a vacuum, and the door 21 cannot be opened until the evacuated condition of the chamber is relieved by a closing of the valve.

A pair of steaming rollers function within the vacuum chamber, one being designated the first seaming roller 74, and the other the second seaming roller 75. The rollers are rotatably carried as at 76 at the respective ends of a double crank member 77 supported on the lower end of a stem 78. This stem is vertically disposed and oscillatable in a bearing bore 79 and extends upwardly through said bore and through an oil seal bearing 80 formed in a hub 81 eccentrically positioned on a disk 82. The disk 82 is adjustably clamped in a housing recess 83 through the medium of the clamp ring 84. A handle member 85 including a depending stop vane 86 is secured upon the extended end of the stem 78, said handle member being oscillatable between adjustable stop screws 87 for the purpose of alternately presenting the seaming rollers 74 and 75 for engagement with a can being rotated by the chuck for turning the sealing seam thereon. See Figures 45, 5, 6, 8, 9 and 10.

As the handle is pushed away from the operator, the roller 74 performs the first seaming function, and as the handle is then pulled toward the operator, the second or final seaming function is performed by the roller 75. This function of alternately presenting units of a pair of seaming rollers for seaming engagement with a can being rotated by a rotary chuck is known in the art and it is thought to be unnecessary further to dwell upon the details concerning the structure and function of said rollers. An example of structures of this type is to be found in the patent to Kronquest #2,023,598 issued December 10, 1935.

By adjusting the disk 82 about its axis the spacing between the axes of the eccentrically disposed stem 78 and the chuck carrying shaft 11 may be varied to adapt the seaming rollers 74 and 75 to seaming engagement with cans of varied diameters.

A gage 88 may be mounted on the housing 19 to indicate pressure conditions in the vacuum chamber.

In operation, a can is placed through the open door 21 onto the pad 37 and the treadle 42 is depressed to raise the pad toward the chuck. The treadle moves the control rod 34 and the projected stop rod head 56 engages the stop collar 61 to halt upward movement of the can when its top 75

still is spaced from the chuck as at 64. See Figure 6. The door 21 is now closed and the handle 11 is manipulated to move the valve to the open position for the purpose of evacuating the seaming chamber. Just before the valve reaches its fully open position the handle lever extension 72 strikes the stop rod abutment 59. The operator continuing to open the valve fully withdraws the stop head 56 and allows the treadle to be depressed to the limit and the can to be thus lifted against the rotating chuck. The can is now seamed by alternately pushing and pulling the lever handle 85 as hereinbefore described.

In order to remove a seamed can the valve is moved to its closed position to relieve the evacuated condition in the seaming chamber by opening said chamber to atmosphere. The treadle is released to lower the pad, and with the pressures inside and outside the chamber now balanced the door 21 can be opened and the can removed.

As previously stated, the chuck spindle, the pad column, and the seaming roller supporting stem all are mounted in oil seal bearings cooperating with the door gasket in providing an air tight seaming chamber. During trial operations it has been demonstrated that from five to fifteen cans can be vacuum-sealed per minute, and 28 inches of vacuum was registered in the vacuum chamber and 26 inches in a number two and one half standard empty can mounted in said chamber.

What I claim is:

1. In apparatus for sealing containers in a vacuum, the combination of a vacuum chamber, means in the chamber for sealing a container and including a rotary chuck and a pad reciprocable to present a container to said chuck, a valve operable to bring about or relieve an evacuated condition in said chamber, stop means normally effective to stop movement of said pad just prior to engagement between said chuck and the cover of a loosely covered container on said pad whereby said cover will be loosely held against displacement, and means for rendering said stop means ineffective as said valve is moved to the position in which an evacuation of said chamber is effected.

2. In apparatus for sealing containers in a vacuum, the combination of a vacuum chamber, means in the chamber for sealing a container and including a rotary chuck and a pad reciprocable to present a container to said chuck, a valve movable between fully open vacuum creating and fully closed vacuum relieving positions, means for preventing movement of said pad to engage a container with said chuck, and means connected to said valve and positively actuated during movement of said valve to its fully open position for rendering ineffective said movement preventing means.

3. In apparatus for sealing containers in a vacuum, the combination of a vacuum chamber, means in the chamber for sealing a container and including a rotary chuck and a pad reciprocable to present a container to said chuck, a valve movable between fully open vacuum creating and fully closed vacuum relieving positions, manually operable means for reciprocating the pad, a rod movable with said pad reciprocating means and having a stop collar thereon, a stop rod normally positioned to engage said collar and prevent movement of said pad toward said chuck sufficient to engage a container with said chuck, and means movable with the valve during move-

ment toward its open position for shifting said stop rod to a release position.

4. In apparatus for sealing containers in a vacuum, the combination of a vacuum chamber, means in the chamber for sealing a container and including a rotary chuck and a pad reciprocable to present a container to said chuck, a valve movable between fully open vacuum creating and fully closed vacuum relieving positions, manually operable means for reciprocating the pad, a rod movable with said pad reciprocating means and having a stop collar thereon, a stop rod normally positioned to engage said collar and prevent movement of said pad toward said chuck sufficient to engage a container with said chuck, and means movable with said valve during movement toward its fully open position for engaging said stop rod and retracting it to a release position just prior to attainment by said valve of its fully open position.

5. In apparatus for sealing containers in a vacuum, the combination of a vacuum chamber, means in the chamber for sealing a container and including a rotary chuck and a pad reciprocable to present a container to said chuck, a valve movable between fully open vacuum creating and fully closed vacuum relieving positions, manually operable means for reciprocating the pad, a rod movable with said pad reciprocating means and having a stop collar thereon, a stop rod normally positioned to engage said collar and prevent movement of said pad toward said chuck sufficient to engage a container with said chuck, spring means for holding said stop rod in its normal position, an abutment collar on said stop rod, and a lever movable with said valve and engageable with said abutment collar just prior to attainment by said valve of its fully open position for retracting said stop rod to a release position.

6. In apparatus for sealing containers in a vacuum, the combination of a vacuum chamber, container sealing equipment in the chamber including a chuck and a container support, means for bringing about relative movement between the support and the chuck to effect engagement between the chuck and a container mounted on the support, stop means normally effective to stop the relative movement just prior to engagement between said chuck and the cover of a loosely covered container on said pad whereby said cover will be loosely held against displacement, a valve movable to effect an evacuated condition in the chamber, and means actuated during completion of movement of the valve to its evacuation effecting position for removing said stop means.

7. In apparatus for sealing containers in a vacuum, the combination of a vacuum chamber, container sealing equipment in said chamber including a chuck and a container support, means for moving the support to present a container for contact with the chuck, stop means effective to limit movement of the support beyond a predetermined extent so as to prevent completion of movement of the support to present containers for contact with the chuck, a valve manually movable to an open position to effect an evacuated condition of the chamber, and means movable with the valve to its open position for mechanically engaging and moving the stop means to an ineffective position.

8. In apparatus for sealing containers in a vacuum, the combination of a vacuum chamber, container sealing equipment in said chamber including a chuck and a container support, means

- for moving the support to present a container for contact with the chuck, stop means effective to limit movement of the support in position to present containers close to but spaced slightly from the chuck so that the chuck will prevent displacement of the loosely applied covers, a valve manually movable to an open position to effect an evacuated condition in the chamber and to another position to relieve the evacuated condition, means movable with the valve and effective as the valve approaches its fully open position to move the stop means to an ineffective position, and means operable upon movement of the valve to said another position to return said stop means to its effective position.
9. In apparatus for sealing containers in a vacuum, the combination of a vacuum chamber, con-

tainer sealing means including a container supporting element and a chuck element, means for bringing about relative movement between said elements to cause the chuck element and a container to engage or disengage, means normally limiting relative movement between the elements so that a loosely applied cover on the container will closely approximate and be held in place by said chuck without tightly engaging it, a valve movable to effect an evacuated condition in the chamber, and means movable by actuation of the valve to its chamber evacuating position for displacing said movement limiting means to permit the container and the cover loosely applied thereon to be tightly engaged with the chuck. 15

GERALD L. ARDRON.
